SELF-TIMER FOR CAMERA SHUTTER

Kenneth A. Van Dyck, Rochester, N. Y., assignor
to Eastman Kodak Company, Rochester, N. Y.,
a corporation of New Jersey

Application February 11, 1949, Serial No. 793

Term of patent 7 years

(Cl. D61—1)

To all whom it may concern:

Be it known that I, Kenneth A. Van Dyck, a citizen of the United States, residing in Rochester, in the county of Monroe and State of New York, have invented a new, original, and ornamental Design for Self-timer for Camera Shutter, of which the following is a specification, reference being had to the accompanying drawings, forming a part thereof, in which:

Fig. 1 is a perspective view of a self-timer for camera shutter showing the front and parts of the top and side walls of my new design;

Fig. 2 is a view similar to Fig. 1, also in perspective but showing the rear wall and parts of a top and side wall thereof; and

Fig. 3 is a side elevation of the design shown in the preceding figures.

I claim:

The ornamental design for a self-timer for camera shutter, as shown.

KENNETH A. VAN DYCK.
